UNITED STATES PATENT OFFICE.

AUGUST WEINRICH AND CLEMENS WEINRICH, OF WORBIS, GERMANY.

PYROTECHNIC TOY.

No. 909,265.

Specification of Letters Patent. Patented Jan. 12, 1909.

Application filed September 25, 1907. Serial No. 394,565.

To all whom it may concern:

Be it known that we, AUGUST WEINRICH and CLEMENS WEINRICH, both subjects of the German Emperor, and both residing at 5 Worbis, in the German Empire, have invented certain new and useful Improvements in Pyrotechnic Toys, of which the following is a specification.

Our invention relates to those pyrotechnic 10 toys which are known as coruscating or Bengal-candles and which on being ignited emit showers of bright sparks. With a view to producing the illusion of a luminous ring or "sun" shedding sparkling rays, means have 15 been provided whereby such candles can be swung round in the hand. We have ascertained that the color effects of such a rotating candle can be greatly increased by providing the candle with two separate masses of in- 20 flammable composition, which may be such as to burn with different colors, the one mass emitting for instance a red light and the other mass a blue light. The masses may be of equal or unequal lengths and may lie in 25 the same plane of rotation or in different planes. To enable the thus constructed double-candle to be conveniently swung, the stem which unites the two combustible masses presents a bearing to receive a rod, 30 spindle or other member acting as axis of rotation.

Our invention is illustrated in the accompanying drawing.

Figure 1 shows a double-candle with parallel masses of composition united by a simple bent stem. Fig. 2 shows a modification in which the connecting stem is crossed at the bearing part. Fig. 3 shows a double-candle whose connecting stem is spirally wound to constitute the bearing. Fig. 4 shows a modified form of double-candle, the connecting stem being a straight wire presenting an eye.

In the double-candle shown in Fig. 1 the 45 two parallel masses of composition a are connected by a stem b , which is a wire simply bent back on itself to form a bearing for a spindle, rod or the like c adapted to be held

in the hand. Or instead of a spindle a finger of the hand itself may be employed as axis. 50

In the modification illustrated in Fig. 2 the two masses of composition a^1 a^1 are splayed apart, the connecting stem b^1 being crossed to form a loop to receive the spindle or the like c^1 or a finger of the hand. 55

The stem of the candle shown in Fig. 3 is spirally coiled to form a sleeve bearing d . The two inflammable masses e e^1 of this candle thus lie in different planes of rotation.

In the candle shown in Fig. 4 the bearing 60 for the spindle is a mere eye g , formed by simply bending round the straight wire stem. In this candle the limbs with combustible masses f f^1 on the two sides of the eye are shown as being of unequal length. 65

It is apparent that the relative position of the inflammable masses to each other may be other than in the illustrated examples; and the form of the bearing also may be varied. 70

What we claim as new and desire to secure by Letters Patent is—

1. A coruscating double-candle, comprising two masses of combustible composition, and a stem uniting the same and presenting 75 a bearing to receive a member about which the candle can be swung.

2. A coruscating double-candle, comprising two masses of combustible composition, and a stem uniting the same and bent to 80 form a bearing for a member about which the candle can be swung.

3. A coruscating double-candle, comprising two masses of combustible composition, and a stem uniting the same and presenting a 85 bearing, in combination with a member adapted to be grasped by the hand, and inserted through the bearing, and serving as axis about which the candle can be swung, substantially as described. 90

4. A coruscating double-candle, comprising two masses of combustible composition, and a stem uniting the same and bent to form an eye adapted to receive a member about which the candle can be swung. 95

5. A coruscating double-candle, comprising

ing two masses of combustible composition, and a stem uniting the same and spirally twisted to form an elongated eye adapted to receive a member about which the candle

can be swung.

6. A cornuscating double-candle, consisting of two limbs of unequal length coated with masses of combustible composition and presenting at their place of junction a bearing

adapted to receive a member about which the candle can be swung.

In testimony whereof we affix our signatures in presence of two witnesses.

AUGUST WEINRICH.
OLEMENS WEINRICH.
